UNITED STATES PATENT OFFICE.

EDWARD STONE, OF CORTLAND, NEW YORK, ASSIGNOR OF ONE-HALF TO
JOHN HODGSON, OF SAME PLACE.

RAILROAD-SWITCH.

SPECIFICATION forming part of Letters Patent No. 292,145, dated January 15, 1884.

Application filed July 18, 1883. (No model.)

To all whom it may concern:

Be it known that I, EDWARD STONE, a citizen of the United States, residing at Cortland, in the county of Cortland and State of New York, have invented certain new and useful Improvements in Railway-Switches; and I do hereby declare the following to be a full, clear, and exact description of the invention, such as will enable others skilled in the art to 10 which it appertains to make and use the same, reference being had to the accompanying drawings, and to the letters or figures of reference marked thereon, which form a part of this specification.

15 My invention relates to railroad-switches; and the novelty consists in the construction, arrangement, and adaptation of parts, as will be more fully hereinafter set forth, and specifically pointed out in the claims.

20 The object of the invention is to provide a construction that will be simple, uncomplicated, and inexpensive, but also one that may be readily manipulated with one-half the force ordinarily employed, which shall be safe and durable; and to these ends the invention 25 consists in the mechanisms fully illustrated in the accompanying drawings, which form a part of this specification, and in which—

Figure 1 is a plan view, showing the main 30 track open in full lines and the switch-track open in dotted lines, broken away to show the rail-springs. Fig. 2 is a vertical section through the switch-box, and Fig. 3 a detail perspective of the oscillating cam-plate and its bearings.

Referring to the drawings, in which similar letters of reference indicate like parts in all the figures, A designates one rail of the main track, which is continuous, and A' the other 40 rail of the main track, said rail A' having the ordinary frog, J, and sliding rails K. The main rail A' in one direction connects with the frog on the adjacent main track, (not shown,) and the frog J on the rail A' connects directly with the main rail on the adjacent main track in the same direction. I have only shown the construction of one track; but it will be understood that an adjacent track 45 is contemplated of similar construction, but in reverse arrangement as regards position.

In my invention a portion of the main rail is movable. The piece B has a pivot-bearing at b, and has its free end beveled, to make the main track complete at b', thus necessitating but a single frog.

55 The switch-rail C has a pivotal bearing at c, and is beveled, as at c', to lie close to the main rail A, while a stout spring, C', serves with a constant force to hold this rail away from the rail A when the main track is open. In a 60 similar manner a stout spring, B', serves with a constant force to hold the rail B away from the rail A' when the switch is open, the bevel b' at such times serving as a guard. The switch is operated by a cam-plate, G, having 65 arms G', each provided with an incline bearing, g, which, when its appropriate switch-rail is locked in place, is directly opposite the pivot of the plate G, thus giving an extended bearing and a firm lock to the rail. The cam-plate G is connected by a rod, D, pivoted at 70 one end to an arm, g', of said cam-plate, and loosely pivoted at its opposite end to an arm, d, rigid with a rotary standard, D', journaled within a box, E, as shown. An arm or lever, 75 F, rigidly secured to the rotary standard, works in a segmental slot, g'', in the box E, and pins x, serving in perforations x', operate to lock said lever at the end of its stroke in either direction.

80 Referring to Fig. 1, it will be observed that the first action resulting from a stroke of the lever F will be to open the switch-track by throwing the switch-rail C over against the rail A, the next to release the switch-rail B, 85 and finally to securely lock the rail C firmly in place, the spring B' having simultaneously thrown the switch-track entirely open by moving the rail B.

85 The operation of the cam-plate G, in connection with the switch-rails B and C, and the results accruing from the springs B' and C', are important. It will be observed that only sufficient force to move one of the switch-rails need at any time be applied. The cam-plate 90 G is pivoted at h in a proper frame, H, and its bearings are such as to give the least possible amount of friction.

95 Modifications in details of construction may be made without departing from the principle.

ple or sacrificing the advantages of my invention, the essential features of which are herein described, so as to be understood by those skilled in the art.

Having thus fully described my invention, what I claim as new, and desire to secure by Letters Patent of the United States, is—

1. In combination with the rails B and C and the cam-plate G, whereby they are both forced outwardly, the springs B' and C', adapted to serve substantially as herein specified.
2. In combination with the rails B and C,

main rails, and springs B' and C', as shown, the cam-plate G, having arms G', with inclined bearings g, the pivot h, rod D, standard D', lever F, box E, having slot g², and the locking-pins x, as and for the purposes set forth.

In testimony whereof I affix my signature in presence of two witnesses.

EDWARD STONE.
